SYSTEMS FOR SEPARATING NITROGEN FROM NATURAL GAS

Pierre E. Haynes, Indianapolis, Ind., assignor to Koppers Company, Inc., a corporation of Delaware

Application April 20, 1950, Serial No. 157,141

8 Claims. (Cl. 62—123)

The present invention relates to the removal of nitrogen from natural gas and more particularly to improvements in processes of reducing the nitrogen content of natural gas in the course of recompression during transmission from its source to the place of its consumption.

Extensive facilities have been provided, and additions thereto have been contemplated, for transporting natural gas over long distances, particularly by way of long cross-country pipe lines. Since the value of natural gas for use as fuel and for other purposes depends mainly on its hydrocarbonaceous constituents, including principally methane, and smaller proportions of other alkanes such as ethane, propane, butane and others, the removal of an incombustible constituent such as nitrogen, particularly before transmission of nitrogen-bearing natural gases for long distances, has become an important consideration.

Besides hydrocarbons and nitrogen, natural gas coming from existing wells is known to contain hydrogen sulfide, carbon dioxide, helium and water vapor. It is customary to remove hydrogen sulfide and water from natural gas in the vicinity of its source, in view of the respective corrosiveness and hydrate-forming tendencies of these constituents. It is also common practice to remove and recover heavy and more readily condensable hydrocarbons. It has not been customary in actual practice to remove nitrogen, carbon dioxide and helium from natural gas before transmission through pipe lines to distant places of utilization.

Of the aforementioned latter three gases, nitrogen is found present in natural gas in much larger proportions than either of the others. In some cases, the proportion of nitrogen is as high as eighty percent, depending on the location of a reserve. It has been recognized that the removal from natural gas of excess nitrogen ("excess" is considered by some authorities to be ten percent or more) should result in important benefits, and that its presence has certain objectionable features among which are the following:

A. It causes a reduction in heating value and may limit the marketability of the gas if the heating value is less than accepted standards for such fuel.

B. It may limit the separation and recovery of the heavier hydrocarbons from the gas for separate sale as natural gasolines and low pressure gas, because the removal of these heavier hydrocarbons causes a further reduction in heating value of the residual gas.

C. It imposes a burden on the gas transportation and distribution facilities by reducing the capacity of such facilities to transport maximum amounts of combustible gas.

D. It may reduce the efficiencies of operations such as carbon black production and liquefied gas storage for peak load demand.

The present invention includes improvements in processes whereby nitrogen is removed from nitrogen-bearing natural gas with efficiency and economy on a

2

commercial scale. The invention further includes processes and means whereby advantages are gained which result from overcoming any one or more of the above-mentioned objections. Not only does the removal of nitrogen result in an increase in fuel value of natural gas, there is also an improvement in the flow characteristics of the gas as a result of an appreciable reduction in the specific gravity and a decrease in viscosity. The net effect of removing nitrogen from natural gas is to increase substantially the volumetric deliverability, and consequently the B. t. u. deliverability, of a transmission system. Furthermore, it can be demonstrated that the economic benefits from nitrogen removal increase in nearly direct proportion to the percentage of nitrogen removed and the distance the gas is transported.

For the removal of nitrogen from nitrogen-bearing natural gas, nitrogen separated from the gas, in the present process, is effectively employed as a cooling medium for condensing out methane, and other hydrocarbons if present. During the condensation step which is conducted while maintaining the natural gas under pressure, uncondensed nitrogen separated from liquefied methane is expanded with performance of external work, and the required cooling is performed with the thus expanded nitrogen. Under conditions hereinafter indicated, no other cooling means and no extraneous refrigerants are found necessary. Furthermore the number of heat exchangers in the system may be reduced to a minimum.

In a more specific application of the invention to removal of nitrogen while natural gas is in transit in long pipe lines, advantage is taken of the use of the pressure employed to send the gas to its destination, as well as of the nitrogen content of the gas. Provision is made for adjustment of the proportion of nitrogen and for recycling thereof as needed while maintaining the pressure of the natural gas during separation of nitrogen therefrom. Not only is an appreciable saving of energy thereby realized but also a saving in the cost of equipment.

The nature of the invention is further described in detail hereinbelow by way of exemplification, and with reference to the accompanying drawing in which is shown diagrammatically a preferred arrangement of apparatus suitable for carrying out steps in the process claimed.

In the figure shown in the drawing, apparatus for continuous removal of nitrogen from natural gas is illustrated which comprises a heat exchanger 1, a condenser 2 provided with a liquid receiver 3, a turbine 4, and piping for the system described hereinbelow.

Gas purification means, represented by the rectangle 5, are provided for the pretreatment of natural gas, when necessary, for the removal of such constituents as carbon dioxide, water vapor, hydrogen sulphide, and the heavier hydrocarbons. Such constituents, when present, are each removed in a well-known or appropriate manner including physical and/or chemical methods.

A pipe 6 is provided for conducting nitrogen-bearing natural gas under pressure from a source to the aforesaid pretreatment means 5. From thence, a pipe 7 conducts the pretreated gas to the warm end of the heat-exchanger 1. A pipe 8 and valves 9 and 10 are provided for bypassing the pretreatment means 5.

Pipes 7 and 8 are connected to piping 11 in the heat-exchanger 1. A pipe 12 connects piping 11 to the liquid receiver 3 of the condenser 2. A pipe 13 is provided for conducting uncondensed gas out of the condenser tubes 14 of the condenser 2. The pipe 13 is connected to a pipe 15 provided with a valve 16, and to a pipe 17 provided with a valve 18. The pipe 15 is connected to piping 19 in the heat-exchanger 1. Pipe 17 and piping 19 are connected to a pipe 20 which leads to the turbine 4. Expanded gas from the turbine 4 is conducted through a pipe

21 into the cooling space 22 surrounding the condenser tubes 14. A pipe 23 connects the space 22 to a pipe 24 provided with a valve 25, and to a pipe 26 provided with a valve 27. The pipe 26 connects the pipe 23 to the heat-exchanger 1, and the pipe 24 connects the pipe 23 to a heat-exchanger 28. A pipe 29 connects the exchanger 28 to the pipe 26.

A pipe 30 is provided for conducting condensate from the receiver 3 of the condenser 2 through the heat-exchanger 28 to a pump 31. The delivery pipe 32 of the pump 31 is connected to piping 33 in the heat-exchanger 1 which in turn is connected to a pipe 34 for emitting purified methane from the system.

A pipe 40 connected to the heat-exchanger 1 serves to conduct separated nitrogen to recycling means, and to a pipe 41 provided with a valve 42 which is opened when nitrogen is emitted from the system. For recycling nitrogen through the system, a pipe 43 having a valve 44 connects the pipe 40 to a compressor 45, and a pipe 46 connects the compressor 45 to the pipe 6. A pipe 47 leading to the compressor 45 and having a valve 48, is provided for introducing nitrogen into the system when needed for the purposes set forth hereinbelow.

The above apparatus is provided to serve primarily as an auxiliary system for the treatment of natural gas to remove nitrogen. The system is brought into operation by connecting the pipe 6 to a source of nitrogen-bearing natural gas under sufficiently high pressure. When coming direct from a well or reserve, the gas usually requires a preliminary purification in which case it is subjected to treatment in purification means 5, under the incoming pressure, for the removal of such impurities as hydrogen sulphide, carbon dioxide, and water, and for the separation of heavier hydrocarbons.

In natural gas transmission systems now in use, the gas arrives at a recompression plant at a pressure of about 500 to 550 pounds per square inch and is recompressed to a pressure of about 700 to 750 pounds per square inch. Prior to recompression in such transmission systems, the above-described apparatus performs its function in a manner to be explained below.

If the gas contains any one or more of the above-mentioned constituents which are to be removed first, if desired, the valve 9 is kept open and the valve 10 is shut. If the treatment of the gas for the removal of such constituents is not considered necessary, the valve 9 is shut and the valve 10 in the pipe 8 is opened. Natural gas, preferably substantially free of the above-mentioned impurities and heavier hydrocarbons, passes at the incoming pressure through the piping 11 in the heat-exchanger 1 and through the pipe 12 to the receiver 3 of the condenser 2 wherein cooling is effected to condense preferably substantially all of the methane and other low-boiling hydrocarbons while under pressure of the incoming natural gas.

The nitrogen gas which separates from liquefied methane passes out of the condenser tubes 14 and is conducted through the pipe 13. Part of the nitrogen passes successively through pipes 15 and 19 to pipe 20, and part through pipe 17 to pipe 20 which leads to the turbine 4 where it is expanded to about atmospheric pressure with performance of external work. The resulting cooled nitrogen passes through pipe 21 into the space 22 around the condenser tubes 14 to serve as the cooling medium for the natural gas. The valves 16 and 18 are adjusted so that the gas receives the desired superheat in the heat-exchanger 1. It is preferred that the nitrogen remain in gaseous state in the cooling space in the condenser 2. It is also preferred that the temperature of the nitrogen be sufficiently lowered not only for the purpose of eliminating practically all the methane from the gas in the condenser, but also to subcool liquid methane in the heat-exchanger 28 and to maintain it in liquid form as it passes from the receiver 3 to the pump 31.

The subcooled methane, or purified natural gas, is pumped by the pump 31 through the pipe 32 and piping

33 in heat-exchanger 1 from which it emerges in pipe 34 at about atmospheric temperature and is delivered to a transmission line.

The expanded nitrogen passing from the space 22 through pipe 23 is preferably divided into two streams one of which passes through the valve 25 in pipe 24 to the heat-exchanger 28 for the purpose indicated above, and the other of which passes through pipe 26. The part of the nitrogen serving to subcool the methane passes from the heat-exchanger 28 through the pipe 29 to join with the balance of expanded nitrogen from pipe 23 passing through the valve 27. The valves 25 and 27 are adjusted to apportion the nitrogen for obtaining the desired subcooling in the heat-exchanger 28.

The nitrogen from pipe 26 is brought into indirect heat-exchange relationship with the nitrogen passing to the turbine 4 in piping 19; with the incoming natural gas in piping 11; and with the outgoing natural gas in piping 33. The nitrogen emerges from the exchanger 1 into the pipe 40 at about atmospheric temperature. The nitrogen may be recycled, when required in the system, through the valve 44 in the pipe 43 connected to the compressor 45 which raises the pressure of the recycled nitrogen and feeds it through the pipe 46 into the pipe 6 at substantially the pressure of the incoming natural gas. If nitrogen is needed in the system at commencement of operations or during operation, it can be admitted through pipe 47. Nitrogen that is removed from the gas and that is not needed in the system can be withdrawn from the system through the valve 42 in pipe 41 and can be used in ammonia synthesis and for other purposes.

It is seen from the above description that adjustment of the proportion of nitrogen in the natural gas brought to the system can be readily made to a preselected percent when necessary, or when desired, and for obtaining substantially complete removal of nitrogen. A maximum proportion of 35 per cent nitrogen in natural gas is found to render the process self-sufficient. When the nitrogen in the natural gas under treatment is present in a proportion above the selected maximum, nitrogen that is separated from the gas in the system is not recycled, but is withdrawn from the system through the pipe 41. When the proportion of nitrogen in natural gas from a given source is less than the selected maximum proportion, adjustment of the nitrogen content of such gas is made to this latter proportion as the gas enters the system at the pipe 6. Such selected proportion is substantially continuously maintained, if desired, by regulation of valve 48 when necessary, and by regulation of the valves 42 and 44. Samples of the incoming natural gas may be taken at suitable intervals to ascertain the nitrogen content of the gas. The volumetric addition of nitrogen to be made to the gas can be determined with meters, as is well understood.

By way of further illustration, the following specific example of the process is set forth:

Nitrogen-bearing natural gas which has been preferably pretreated to remove, substantially completely, undesirable constituents other than nitrogen as referred to above, is passed into the piping 11 in heat-exchanger 60 1 at a temperature of about 27° C. and a pressure of 500 to 550 pounds per square inch. If the incoming gas contains 15 per cent nitrogen, additional nitrogen is mixed with the gas to bring the nitrogen content up to, for instance, 35 per cent, while maintaining the latter pressure. 65 The gas at such pressure is cooled by nitrogen entering the condenser 2 at about 83° K. This nitrogen is the nitrogen that is separated from natural gas in the condenser 2, and that is conducted through pipe 13, is provided with controlled superheat, and arrives at the turbine 4 at about 190° K. and about 500 to 550 pounds pressure, and is expanded to lower its temperature to the aforesaid 83° K. or preferably a little above its boiling point, or substantially or materially below the boiling point of methane at the pressure of the natural 70 gas.

The natural gas from which nitrogen is thus removed, passes out of the receiver 3 at about 180° K. under the initial pressure and in liquid form. This liquid is further cooled to about 165° K. by expanded nitrogen from the cooling space 22 of the condenser 2. The processed natural gas leaves the heat-exchanger 1 through pipe 34 at about 27° C. When the system is installed in a recompression plant, the pressure of the processed gas needs only to be raised from the pressure in the system up to or preferably slightly above outgoing transmission line pressure.

The expanded nitrogen from the condenser 2 and heat-exchanger 28 brought together in heat-exchanger 1, emerges from the latter exchanger at about 27° C. and is recompressed to the pressure of the incoming natural gas and recycled through the system, as it is needed, to bring the nitrogen content of the gas up to the preselected proportion or, as in this example, up to about 35 per cent by volume, or so that substantially one-third of the volume of the resulting mixed gases is nitrogen.

The invention hereinabove set forth is embodied in particular form and manner but may be variously embodied within the scope of the claims hereinafter made.

I claim:

1. In a process of removing nitrogen from nitrogen-bearing natural gas, steps comprising while passing said natural gas under pipeline pressure through a gas separation system, adding nitrogen to said natural gas at said pressure to raise its nitrogen content from a given lower proportion to a higher preselected proportion to obtain upon subsequent separation and expansion of said nitrogen a lowering of its temperature materially below the boiling point of methane at said pressure, cooling the resulting mixture in said system at said pressure to liquefy substantially completely all methane while separating uncondensed nitrogen from said liquefied methane, expanding said uncondensed separated nitrogen with performance of external work to lower the temperature of said separated nitrogen materially below the boiling point of methane as aforesaid and passing the expanded nitrogen into indirect heat-exchange relationship with said mixture to effect said cooling to liquefy said methane as aforesaid, and withdrawing substantially nitrogen-free natural gas from said system.

2. In a process of removing nitrogen from nitrogen-bearing natural gas, steps comprising while passing said natural gas under pipeline pressure through a gas separation system, adding nitrogen to said natural gas at said pressure to raise its nitrogen content from a given lower proportion to a higher preselected proportion to obtain upon subsequent separation and expansion of said nitrogen a lowering of its temperature materially below the boiling point of methane at said pressure, cooling the resulting mixture in said system at said pressure to liquefy substantially completely all methane while separating uncondensed nitrogen from said liquefied methane, expanding said uncondensed separated nitrogen with performance of external work to lower the temperature of said separated nitrogen materially below the boiling point of methane as aforesaid and passing the expanded nitrogen into indirect heat-exchange relationship with said mixture to effect said cooling to liquefy said methane as aforesaid, compressing to said pipeline pressure expanded nitrogen coming from the aforesaid cooling step and adding it to natural gas entering said system to adjust its nitrogen content in the manner and for the purpose aforesaid, and withdrawing substantially nitrogen-free natural gas from said system.

3. In apparatus for separating nitrogen from nitrogen-bearing natural gas, a heat-exchanger for precooling natural gas under superatmospheric pressure with expanded nitrogen separated from said gas, a condenser for separating said gas into liquefied methane and uncondensed nitrogen under said pressure, means for conducting natural gas from said heat-exchanger into said con-

denser, means for expanding said uncondensed nitrogen with production of external work, means for conducting said uncondensed nitrogen under said pressure from said condenser to said expanding means, said last-named conducting means including control means for adjustably providing said uncondensed nitrogen with superheat, the said expanding means having gas-passage connection to the cooling space of said condenser for exclusive introduction of expanded gas from said expanding means into said cooling space, means for conducting expanded nitrogen from said cooling space of said condenser to said heat-exchanger for precooling said natural gas, and means for withdrawing liquefied methane from said condenser.

4. In apparatus for separating nitrogen from nitrogen-bearing natural gas, a heat-exchanger for precooling natural gas under superatmospheric pressure with expanded nitrogen separated from said gas, a condenser for separating said gas into liquefied methane and uncondensed nitrogen under said pressure, means for conducting natural gas from said heat-exchanger into said condenser, means for expanding said uncondensed nitrogen with production of external work, means for conducting said uncondensed nitrogen under said pressure from said condenser to said expanding means, said last-named conducting means including control means for adjustably providing said uncondensed nitrogen with superheat, said control means comprising a valve in said last-named conducting means for controlling flow of nitrogen gas directly to said expanding means and a valve-controlled pipe-section in said heat-exchanger for bypassing a controlled portion of nitrogen through said heat-exchanger to said expanding means; means for conducting the expanded nitrogen from said expanding means into the cooling space of said condenser, the said cooling space having gas-entry connection exclusively for said expanded nitrogen; means for conducting expanded nitrogen from said cooling space of said condenser to said heat-exchanger for precooling said natural gas, means for withdrawing liquefied methane from said condenser, means for bringing a portion of said expanded nitrogen from said condenser into indirect heat-exchange relationship with said liquefied methane from said condenser to subcool said liquefied methane, and means for conducting said liquefied methane from said last-named means through said first-named heat exchanger in indirect heat-exchange relationship with said expanded nitrogen from said condenser.

5. In apparatus for separating nitrogen from nitrogen-bearing natural gas, a heat-exchanger for precooling natural gas under superatmospheric pressure with expanded nitrogen separated from said gas, a condenser for separating said gas into liquefied methane and uncondensed nitrogen under said pressure, means for conducting natural gas from said heat-exchanger into said condenser, means for expanding said uncondensed nitrogen with production of external work, means for conducting said uncondensed nitrogen under said pressure from said condenser to said expanding means, said last-named conducting means including control means for adjustably providing said uncondensed nitrogen with superheat, means for conducting the expanded nitrogen from said expanding means into the cooling space of said condenser, the said cooling space having gas-entry connection exclusively for said expanded nitrogen; means for conducting expanded nitrogen from said cooling space of said condenser to said heat-exchanger for precooling said natural gas, means for withdrawing liquefied methane from said condenser, means for compressing expanded nitrogen to substantially the pressure of said natural gas entering said first-named heat-exchanger, and means for selectively adding the recompressed nitrogen to said natural gas for raising the nitrogen content of said gas to a preselected proportion.

6. In a process of removing nitrogen from nitrogen-bearing natural gas at pipe line pressures, steps comprising while introducing into a condensing zone at substan-

tially pipe line pressure, natural gas having less than about one-third by volume of nitrogen, adding enough nitrogen at said pressure to increase the nitrogen content to substantially one-third; while substantially avoiding a drop in pressure of the resulting mixture of gases separately removing liquid methane and nitrogen gas from said condensing zone and expanding said separated nitrogen with performance of external work to lower the temperature of separated nitrogen below the boiling point of methane at said pressure, and passing the expanded nitrogen into indirect heat-exchange relationship with mixed natural gas and nitrogen in said zone to effect liquefaction of methane in the mixture, thereby obtaining substantially nitrogen-free natural gas for transmission at pipe line pressure.

7. Apparatus for removing nitrogen from precompressed nitrogen-bearing natural gas, said apparatus comprising a gas separation system, means for introducing said nitrogen-bearing natural gas into said system under incoming pipe line pressure, said system including a condenser for separating liquid methane from said gas at said incoming pipe line pressure, said condenser having a cooling space exclusively for cooling with expanded nitrogen separated from said gas; a pump for pumping separated methane at outgoing pipe line pressure, means for withdrawing separated nitrogen from said system, and a pump for separately returning separated nitrogen to said system at said incoming pipe line pressure for raising the nitrogen content of said gas to a preselected proportion.

8. Apparatus for removing nitrogen from precompressed nitrogen-bearing natural gas in transmission for long distances from its source to a remote destination, said apparatus comprising a gas separation system, means

for introducing said nitrogen-bearing natural gas into said system under pressure employed in said transmission, adjustable means for introducing nitrogen at said pressure for admixture with said gas to adjust the proportion of said nitrogen to obtain upon subsequent separation and expansion of said nitrogen a lowering of its temperature below the boiling point of methane at said pressure, said system including a condenser for separating liquid methane from said gas at said pressure, said condenser having 10 a cooling space for cooling with expanded nitrogen separated from said gas, and means for withdrawing separated methane from said system for delivery under pressure employed in said transmission.
